DESIGN FOR A LAWN MOWER WHEEL HOUSING

Marlowe H. Kluter, Richmond, Ind., assignor to
The F. & N. Lawn Mower Company, Rich-
mond, Ind., a corporation of Delaware

Application April 5, 1939, Serial No. 84,072

Term of patent 14 years

To all whom it may concern:

Be it known that I, Marlowe H. Kluter, a citizen of the United States of America, residing at Richmond, in the county of Wayne and State of Indiana, have invented a new, original, and ornamental Design for a Lawn Mower Wheel Housing, of which the following is a specification, reference being had to the accompanying drawing, forming part thereof.

Fig. 1 is a perspective view of a lawn mower wheel housing showing my new design.

Figs. 2 and 3 are side elevations of the outside and inside faces, respectively, of the wheel housing of Fig. 1.

The characteristic features of the present design are shown in solid lines.

I claim:

The ornamental design for a lawn mower wheel housing, as shown and described.

MARLOWE H. KLUTER.
